S. Moore Jr.

INVENTOR

BY Victor J. Evans

ATTORNEY

UNITED STATES PATENT OFFICE.

SAMUEL MOORE, JR., OF WILMINGTON, DELAWARE.

SHAVING BRUSH.

Application filed July 8, 1924, Serial No. 724,825. Renewed December 15, 1925.

To all whom it may concern:

Be it known that I, SAMUEL MOORE, Jr., a citizen of the United States, residing at Wilmington, in the county of New Castle and State of Delaware, have invented new and useful Improvements in Shaving Brushes, of which the following is a specification.

This invention relates to a shaving brush, 10 the general object of the invention being to provide means whereby the brush can be attached to a tube of shaving cream so that the tube will act as a handle and with means whereby some of the cream in the tube can 15 be ejected into the bristles of the brush.

Another object of the invention is to provide means whereby the cream being forced into the bristles can be seen.

This invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the 30 several views, and in which:—

Figure 1 is a sectional view through the brush head showing the same attached to a tube.

Figure 2 is an elevation showing the device on a tube.

Figure 3 is a section on line 3—3 of Figure 2.

In these views, 1 indicates a brush head 40 which is provided with an annular flange 2 to support the bristles 3. Said head, in its outer end, is provided with a tapered recess 4 for receiving the sloping end of a collapsible tube 'A' which contains shaving

cream or the like. The head is also provided with a threaded bore 5 for receiving the 45 threaded nipple 'a' of the tube and with a hole 5' which permits the cream to pass from the mouth of the tube 'A' into the bristles. The flange 2 is provided with a slot 6 and the bristles are so placed in the head that 50 an elongated opening 7 is left which registers with the slot 6 so that the cream being forced into the bristles can be seen through the openings 6 and 7. Thus the desired amount of cream can be pressed from the 55 tube. As will be seen the tube acts as a handle for the brush and when a person wishes to shave it is simply necessary to squeeze the tube slightly to force the desired amount of cream into the bristles of 60 the brush and then use the brush in the regular manner. The engagement of the brush head on the threaded nipple of the tube and the engagement between the recessed part of the head and the sloping 65 shoulders at the end of the tube will firmly connect the brush head with the tube.

It is thought from the foregoing description that the advantages and novel features of my invention will be readily apparent. 70

I desire it to be understood that I may make changes in the construction and in the combination and arrangement of the several parts, provided that such changes fall within the scope of the appended claim. 75

What I claim is:—

A device of the class described comprising a brush head having a hole passing through the same and a slot in one side which communicates with the hole, said slot extending 80 into the bristle part, the under portion of the hole being threaded to receive the threaded nipple of a cream tube.

In testimony whereof I affix my signature.

SAMUEL MOORE, JR.
